UNITED STATES PATENT OFFICE

1,970,561

TROPICAL CONCRETE CONSTRUCTION

John E. Grant, Manila, Philippine Islands, assignor to Margaret T. Yates, New York, N. Y.

Application September 24, 1930, Serial No. 484,019

4 Claims. (Cl. 72—16)

I have discovered that great saving may be had in concrete construction in localities where bamboo is available.

I have further discovered that bamboo is a material preferable over almost any other material for reenforced construction and forms in tropical climates.

The object of my invention is an improved process of concrete construction whereby the forms of an organic material are used and left in the finished product as a reenforcement.

A further object of my invention is the production of an organic form suitable for concrete construction.

15 A further object of my invention is an improved system for forming a concrete structure.

A further object of my invention is the construction of a reenforced concrete structure embracing metallic reenforcing elements and in-organic forming and reenforcing elements.

A further object of my invention is an improved method for holding organic flexible structures in position to form forms for pouring concrete.

With the foregoing and other objects in view, 25 my invention consists of the methods employed, combination and arrangement of systems, apparatus and means as hereinafter specifically set forth and illustrated in the accompanying drawings wherein is shown the preferred embodiment of 30 my invention, but it is understood that changes, variations and modifications may be resorted to which come within the scope of the claims hereunto appended.

In order fully to understand my process of 35 construction, I will now show details of the work. Fig. 1 is a sectional view taken through 1—1 of Fig. 2; Fig. 2 is an enlarged view in elevation of the face of the form before pouring the material; Fig. 3 is a plan view looking downward; Fig. 4 is an enlarged sectional view of a bamboo strand used in the mat construction; Fig. 5 is a sectional view of the corner of a building; Fig. 6 is a view in elevation of the construction shown in Fig. 5; Fig. 7 is a sectional view taken through 7—7 of 45 Fig. 6; and Fig. 8 is a sectional view taken through 8—8 of Fig. 2 before the supporting frame-work is removed.

Bamboo mats are constructed in sections of 50 suitable size; I have found that mats 5 ft. wide and 16 ft. long are convenient for construction for the side walls; for the floors and roof much longer mats may be used to advantage. In the construction of these mats bamboo strands 16 ft. long form the horizontal members; and, when 55 I use the term, "horizontal members", I do not

wish to be limited to the level, as these strands of the mat of which they are a composition may be placed at any angle with reference to the vertical that the construction may require, with reference to the side walls and partitions. In the floors, ceiling and roof the respective layers of bamboo mats are laid alternately cross-wise; i. e., one layer lengthwise of the building and the next layer cross-wise of the building.

I have found, however, that the nearer the horizontal, or level, the bamboo strands are placed the better bonding I obtain, owing to the fact that there is less slip of the soft concrete. These bamboo strands are constructed as shown in cross-section in Fig. 3. The bamboo is split, the pulp removed leaving the solid bamboo with the original outside shell or surface on the outside, the edges being shaped to form angles to facilitate the bonding of the cement or plaster to the strand. The warp is shown substantially in cross-section as outlined in Fig. 3; in other words, it is not particularly shaped. I do not wish to limit myself, however, to the shapes described and shown, as my process and construction may be accomplished with almost any shape laid up in almost any way. I am describing, however, the preferable method as evolved in large building construction in the Philippine Islands.

The mats described are woven ordinarily by the natives by hand, where the bamboo is worked. The construction is shown in detail in Figs. 1, 2 and 3.

To form a wall two of these mats are placed back to back; that is, the face or surface of the bamboo strands are outward on both sides. The mats are wired together at a specific distance apart, say from 3 to 12 inches, or more, according to whether they are to be used as partition walls outside, or heavy supporting walls. This feature is particularly shown in Figs. 1—3, the wiring 10 spacing preferably being on 18 inch centers staggered.

Referring particularly to Fig. 8, the supporting studding or temporary bracing, usually of 2 x 4 wood, is shown, there being placed between the mats and said bracing battens of any suitable shape or size. I have found 1 x 3 to be suitable.

7 is a section of matte, and 8 is the bamboo strand. 9 is the bamboo warp. 10 are the tie wires. 11 are metal anchors. 12 are metal reinforcements. 14 is cement. 15 is concrete. 16 is the finished coat. 17 are battens, and 18 are braces.

Almost all varieties of bamboo growing in the

Philippine Islands are adaptable for this work. The bamboo is split, shaved and formed into strands and warps, as shown in Fig. 4; it is then woven into a mat, and strands with the shell of the bamboo on the outside and the apex on the inside are woven, using a warp of almost any convenient shape.

For the construction of walls, columns, partitions, and other types of concrete construction, 10 woven mesh of bamboo is spaced to the distance that the thickness of the wall may require and held in place by 2 x 4's, or similar size of lumber. I have found that walls and columns of sizes suitable for concrete bungalows can be poured 15 continuously to a height of 12 ft. The vertical members of the supports are placed approximately 2½ feet on centers, the horizontal supports being spaced approximately 3 feet apart. These supports are placed equally on each side 20 of the concrete wall to be poured, to support the bamboo mesh temporarily until the concrete sets. The mesh and supports are both tied by wire of sufficient strength to prevent expansion while the pouring of the concrete takes place.

25 The erection of the bamboo mesh, as well as the supports for the same, requires but little skilled labor and time. The filling of the space between the bamboo mats with concrete requires but little attention, as any voids can readily be detected, the mats being sufficiently open to observe the density of the mixture.

Practically no tamping is required; instead, a little tapping on the outside of the bamboo mesh will cause the concrete to settle into proper place.

30 The surfaces of the walls are always accessible, and can be roughened to any degree desired before the concrete sets so as to leave the surfaces of the wall in the best possible condition to receive the plaster material, tiles, or aggregates, 40 and obtain the best possible adhesion. The cost of roughening the surfaces before the concrete sets is very small.

45 The mortar from the concrete fills most of the voids in the bamboo mesh, causing the bamboo to be imbedded in the concrete to such an extent that the bamboo acts as a very strong reinforcement, being close to the surface where it will have its maximum value in tensile strength. Plaster is applied to the outside surfaces, obtaining an excellent mechanical bond, as well as chemical, as a sufficient amount of mortar from the concrete comes in contact with the plaster.

50 In the setting up of the mat, the horizontal strips of the bamboo mesh are V-shaped, with the point of the V or the apex pointing inwardly, thus causing the plaster to key itself to the mesh. There are also sufficient voids in the mesh after the concrete is poured to provide still further means of mechanical bond.

55 The ordinary system requires the concrete to be roughened or chipped after the removal of the forms. The concrete is then set and hard and requires a great deal of time and expense to place the surface of the wall in proper condition to receive the plaster material. This I avoid in my construction.

60 Due to the cost and time required by the ordinary system of construction, in many instances roughening is not properly done, which later causes the plaster materials to separate from the concrete. This I also avoid.

65 I would state that I am aware that bamboo has been used in the Philippines in some of the old churches for lathing using lime mortar, many of which are very old; also, in some old Spanish

houses. The demolishing of these old buildings has found the bamboo to be in a perfect state of preservation.

70 Metallic reenforcing in the tropics, unless imbedded very deeply in the concrete, oxidizes and expands, breaking away the concrete to a great extent. A great many precautions need to be taken to prevent this from occurring by making the concrete very dense and imbedding the re-enforcing very deeply.

75 Metal lath has been practically disregarded, because of its rapid deterioration. Its intended use by the manufacturers, and the only practical value of the material, is to place the metal lath close to the surface of the concrete and plaster materials, and is worthless in the tropics, as suggested above.

80 Bamboo is not affected by moisture when imbedded under a properly mixed thin coat of cement mortar. Bamboo is abundant all over the Philippines and other tropic and semi-tropic countries, and is very cheap. Mesh can be made of bamboo material for less than half of the cost of metal lath and, in addition, transportation would not have to be considered, as the 85 mesh could be made most anywhere there is likely to be construction work.

90 In this type of bamboo construction, the waste of form lumber would be negligible, as the only form lumber required would be the 2 x 4 supports for the mesh, which could be used many dozens of times over again. Waste in form lumber, which is so great an item in concrete construction, would be entirely eliminated, especially 95 in one-story structures.

100 It has been proved by actual experience that my improved type of construction, in relation to the very costly placing of forms of the ordinary system; the saving of form lumber; the small amount of labor required to roughen the surfaces 105 of the concrete walls; and the almost entire elimination of metal reenforcing,—will greatly reduce the time and cost of concrete construction for walls, columns, partitions, ceilings and other types of concrete construction.

110 In the construction of columns, the mats are formed in circular form and secured in place, then poured and worked as heretofore described in the formation of the side walls.

115 It may be well to here describe the construction of a building, according to my method. First, the foundation of solid concrete is laid, then the walls around and under the building are constructed to the first floor level. The floor is then laid, using closely woven very heavy bamboo the 120 subject matter of another application, a division of this application. The walls are now constructed to the ceiling level, then the ceiling is constructed almost the same as the floor the subject matter of another application, a division of this 125 application, both about 4 inches thick.

130 The roof is now placed in position. This construction is a little different the subject matter of another application, a division of this application.

135 I might state here that I have found it desirable to begin my construction just above the ground levels, say 6 inches above. In the construction of columns and supporting pillars, I have deemed it advisable to reinforce the corners with 140 iron, as shown in the drawings. See Figs. 5 and 6.

145 In this specification and claims, I have been using the term, "concrete" and "concrete construction", rather loosely. I mean, generally, a bonding material which may consist of hydrated 150

cement, lime, or melted plastics; but I do not wish to limit myself to any bonding material. I wish especially to cover the mineral bitumens and asphalt as they are particularly applicable for my work in colder climates, or when stiffened with suitable stiffening materials.

Also, in this specification and claims, when I use the term, "organic material", I have especially described bamboo; but grasses, bagasse, 10 cornstalks, fibre, etc., are very suitable for my work.

In these specifications I have described the construction of bamboo mats. I wish it understood, however, that I do not limit myself to 15 bamboo in this construction, as many other tropical fibers are useful in constructing mats for my forms; among these I might mention the sugar cane, cactus palms and reeds, and many other tropical plants. But I prefer the bamboo as being 20 the larger and more easily worked.

Having thus described my invention, what I claim and desire to secure by Letters Patent is:

1. A wall construction comprising two opposed form members each consisting of two layers of 25 split tropical fiber, said fiber being arranged with the larger arcuate surfaces outwardly and being closely arranged in staggered relation whereby to prevent the seepage of a filling material therethrough, a filling material of concrete within said 30 forms, and a plastic coat on the outside and bonded to said tropical fiber forms.

2. A structure comprising two form members each consisting of layers of split fiber, said fiber

being arranged with the larger arcuate surfaces facing the same side of the form and being closely arranged whereby to prevent an excess of seepage of a filling material therethrough, a filling material of consistency to fill said forms and to a limited extent ooze through said forms between said layers to bind with and form a coating on the exterior of said forms whereby said forms are entirely encased in said materials.

3. A structure comprising two opposed form members each consisting of layers of fiber of split bamboo, said fibers being arranged with the larger arcuate surfaces outwardly and being closely arranged whereby to prevent an excess of seepage of a filling material therethrough, a filling material of concrete to fill said forms and to a limited extent ooze through said forms between said layers to bind with and form a coating on the exterior of said forms, and a bonding material on the exterior of said forms whereby said forms are entirely encased in said materials.

4. A structure comprising two form members each consisting of layers of split bamboo of substantial section, said bamboo being closely arranged whereby to prevent an excess of seepage 100 of a filling material therethrough, a filling material of consistency to fill said forms and to a limited extent ooze through said forms between said layers to bind with and form a coating on the exterior of said forms whereby said forms are 105 entirely encased in said materials.

JOHN E. GRANT.
